UNITED STATES PATENT OFFICE.

GEORGE BALLARD, OF PHILADELPHIA, PENNSYLVANIA.

DESIGN FOR A DOOR-CHECK.

SPECIFICATION forming part of Design No. 33,424, dated October 23, 1900.

Application filed May 29, 1900. Serial No. 18,466. Term of patent 31 years.

To all whom it may concern:

Be it known that I, GEORGE BALLARD, a citizen of the United States, residing at Philadelphia, in the county of Philadelphia and State of Pennsylvania, have invented and produced a new and original Design for Door-Checks, of which the following is a specification.

My invention is a design for door-checks; and it consists of the novel shape and configuration hereinafter fully described, and illustrated in the accompanying drawing.

The drawing represents a view in perspective of a door-check embodying the design. The check is formed from a strip of metal formed at one end with openings 1 and bent upward adjacent to the end to form the inclined portion 2, then downward, forming a

vertical portion 3, then horizontally, as at 4, and terminating in an arm 5, which is bowed upward and has its outer end 6 upturned, as shown. The flat portion 4 is also formed with perforations.

The leading feature of my design is the upwardly-bowed arm 5, having its outer end turned upward.

I claim—

The design for a door-check substantially as shown and described.

In testimony whereof I affix my signature in presence of two witnesses.

GEORGE BALLARD.
